Primary Examiner—Wallace R. Burke**Assistant Examiner**—Freda S. Nunn**Attorney, Agent, or Firm**—Julie L. Schneider; James C. Kesterson; Richard L. Donaldson[57] **CLAIM**

The ornamental design for a replaceable photoreceptor cartridge, as shown and described.

DESCRIPTION

FIG. 1 is a top front and right side perspective view of a replaceable photoreceptor cartridge showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a top rear and left side perspective view thereof.

FIG. 4

FIG. 6

FIG. 5

FIG. 7

FIG. 8
